COMBINED SAW HANDLE, SQUARE, AND
MITERMaurice Elmo Peeples, Kingsland, Ga., assignor
to Kingsland Saw Works, Inc., a corporation of
Georgia

Application June 16, 1947, Serial No. 754,846.

1 Claim. (Cl. 33—75)

1

This invention relates to saw handles and is an improvement over the construction embodied in my copending application, Serial No. 744,942, filed April 30, 1947, for Combined saw handle and square.

An object of this invention is to provide in a saw handle, a countersunk square in one side of the handle, and a countersunk miter in the other side of the handle, the square and miter being spring urged to extended operative position, and releasably latched to inoperative position, whereupon the square and miter are substantially flush with the opposite faces of the handle.

With the above and other objects in view, my invention consists in the arrangement, combination and details of construction disclosed in the drawings and specification, and then more particularly pointed out in the appended claim.

In the drawings,

Figure 1 is a detail side elevation of a saw handle constructed according to an embodiment of this invention, the saw blade being partly broken away,

Figure 2 is a top plan view of the handle,

Figure 3 is a fragmentary sectional view taken on the line 3—3 of Figure 1,

Figure 4 is a fragmentary sectional view taken on the line 4—4 of Figure 1,

Figure 5 is a fragmentary side elevation of the handle opposite from Figure 1,

Figure 6 is a fragmentary sectional view taken on the line 6—6 of Figure 5; and

Figure 7 is a fragmentary sectional view taken on the line 7—7 of Figure 1.

Referring to the drawings, the numeral 10 designates generally a saw blade which is formed with a straight back edge 11 and saw teeth 13 on the opposite edge thereof. A handle generally designated as 12 is secured to the blade 10 by fastening members 14. The handle 12 on one side thereof is formed with a recess 15 extending at right angles from the back edge 11, and is also formed with a recess 16 extending parallel with the back edge 11 and at right angles to the recess 15.

A square member generally designated as 17 is adapted to normally seat in the recesses 15 and 16. The square member 17 includes a right angle metal member 18 which has secured to the outer face thereof a transparent covering 19. A hinge plate 20 is secured by fastening members 21 to the back edge of the handle 12 and the square member 17 is formed with hinge barrels 22 engaging between aligning hinge barrels 23 carried by the hinge plate 20.

2

A pintle 24 extends through the barrels 22 and 23. The square member 17 is adapted to be normally biased to an extended operative position by means of a coil spring 25 disposed in a housing 26 having ears 27 which are secured by fastening members 28 to the upper side of the hinge member 20. The coil spring 25 has extending therethrough a supporting pin 29 which is secured to the opposite ends of the covering or hood 26.

One end 30 of the spring 25 extends downwardly into the handle 12 and the opposite end of the spring extends through a slot 31 formed in the covering or housing 26 and is secured, as at 32, to the metal square member 18. The square member 17 is adapted to be releasably latched in inoperative position within the recesses 15 and 16 by means of a spring pressed bolt or latch member 33 which is formed with a latching bill 34 at its inner end.

The bolt 33 engages under the square member 17, as shown in Figure 3, and the bill 34 engages the inner edge of the square member 17 so as to provide for release of the square member 17 by inward movement of the bolt 33. The bolt 33 is constantly urged outwardly to latching position by means of a spring 35 engaging in an opening 36 formed in the lower portion of the handle 12, one end of the spring 35 bearing against the inner end of the opening 36, and the other end of the spring bearing against an abutment or pin 37 carried by the bolt 33.

An operating knob or button 38 is fixed to the outer end of the bolt 33 and loosely engages in an enlarged counterbore or recess 39 formed in the outer end of the handle 12. A set screw 40 extends through the handle 12 into the recess or bore 39 and provides for limiting the outward movement of the bolt 33 after the square member 17 has been released and is disposed in extended operative position.

The opposite side of the handle 12 is formed with a right angle recess 41 extending from the upper edge thereof and a triangle 42 is adapted to be normally seated in the recess 41. The triangle 42 is formed of a triangular metal plate 43 having secured to the outer side thereof a transparent facing 44. The upper edge of the triangle 42 is hinged to the opposite edge of the hinge plate 20 as indicated at 45 which designate the hinge barrels formed as an extension of the triangle in the same manner as described with reference to the square and in order to provide for holding the triangle 42 at substantially right angles to the adjacent side of the handle 12, a pair

of stop members 46 are fixed to the triangle 42 and are adapted to engage the upper side of the hinge member 20 when the triangle is in extended position so as to maintain the triangle in extended right angular position with respect to the adjacent face of the handle 12.

The triangle 42 is constantly urged to extended position by means of a coil spring 47 similar to the spring 25, which has one end thereof anchored or extended into the handle 12, as indicated at 48. The opposite end of the spring 47 is secured by soldering or other suitable means as indicated at 49 to the metal triangular member 43.

A housing or covering 50 is disposed about the spring 47, being formed at the opposite ends thereof with ears or lugs 51 secured by fastening means 52 to the outer side of the hinge member 20. The housing 50, as shown in Figure 5, is formed with a slot 53 through which one end of the spring 47 extends, this end of the spring extending over the hinge barrels and being fixed to the triangle 43. The triangle 42 is adapted to be normally latched within the recess 41 by means of a spring-pressed latch member 54 similar in every detail to the latch member 33.

The handle 12 on the inner edge of the hand opening 55 is formed with an opening 56 within which the latch member 54 engages, and the handle is also formed with a counterbore 57 within which an operating knob 58 loosely engages. The bolt 54 includes a tapered bill 59 engaging the forward edge of the triangle 42, the bolt engaging under the triangle 42, as shown in Figure 7, so that the bolt will be moved inwardly relative to the recess 56 to released position.

The handle 12 is formed with a rectangular elongated slot 60 within which the bill 59 of the latching bolt loosely engages, and this slot 60 extends through the opening 56. The bolt 54 is constantly urged to latching position by means of a spring 61 which bears at one end against the inner end of the opening or bore 56, and at the other end bears against a pin or abutment 62 carried by the bolt 54. A stop screw 63 is threaded through the handle 12 into the opening or bore 56 in a position where the pin or abutment 62 will strike the stop screw 63 and hold the operating button 58 substantially flush with the outer end of the counterbore 57.

The saw may be used in the conventional manner for sawing wood or the like, with the square 17 and the triangle 42 disposed within the recesses or seats formed in the opposite sides of the handle. Where it is desired to use a square, the square member 17 may be released by pushing the latch member 33 inwardly whereby the square member 17 will be swung outwardly to extended position. This square member 17 may be swung outwardly through an arc of substantially 180°

so that the square member may be engaged with the work. The end portion of the spring 25 which extends from about the pin 29 to be secured to the square 17 extends through the slot 5 and is engageable with one end for limiting the pivoted movement of the square to 180° relative to the handle.

Where it is desired to form a miter, the latch member 54 is moved inwardly by pressure on the release button 58. Spring 47 will swing triangle 42 outwardly to a position at substantially right angles to the adjacent side of the handle 12, and the triangle 42 may then be laid on the face of the work with the handle 12 engaged with the adjacent edge of the work.

This combined saw handle, square and miter will facilitate the work of a carpenter inasmuch as the carpenter will not be required to carry as separate elements a square and a triangle or miter forming member. This handle may be secured to any conventional hand saw blade and will provide a combination tool which will facilitate the work of the carpenter.

I do not mean to confine myself to the exact details of construction herein disclosed, but claim all variations falling within the purview of the appended claim.

What I claim is:

A combined saw handle and tool comprising a handle formed with a recess in at least one side formed downwardly from the back edge of said handle, a tool element formed as a right triangle engageable in said recess, the hypotenuse edge of said triangle having formed as an extension thereof of a half of a hinge with the other half of the hinge being carried by the back of the handle, said other half of the hinge having a top surface disposed normal to the recessed side of the handle, a hinge supporting pin positioned longitudinally of the hinge for swingingly connecting said half hinges, at least one abutment carried by the tool having an under surface formed as an extension of the outer surface of said tool and positioned for engagement with the top surface of said other half hinge on swinging movement of the tool to restrict movement of said tool relative to the handle, and spring pressed latch means carried by the handle for releasably holding said tool in the recess formed in said handle.

MAURICE ELMO PEEPLES.
